UNITED STATES PATENT OFFICE.

JOSHUA W. HARRIS, OF TOWSON, MARYLAND.

COMBINATION DESK AND FILING-CABINET.

1,158,493.

Specification of Letters Patent.

Patented Nov. 2, 1915.

Application filed February 11, 1911. Serial No. 608,074.

To all whom it may concern:

Be it known that I, JOSHUA W. HARRIS, a citizen of the United States, residing at Towson, in the county of Baltimore and 5 State of Maryland, have invented certain new and useful Improvements in Combination Desks and Filing-Cabinets; and I do hereby declare the following to be a full, clear, and exact description of the invention, such as will enable others skilled in 10 the art to which it appertains to make and use the same.

This invention relates to new and useful 15 improvements in cabinets, and more particularly to that class generally known as filing cabinets.

An object of this invention is the provision of a cabinet comprising a series of 20 hinged sections which, when folded, lie in superimposed relation to each other, the lower of the sections being formed so as to produce a base or support for the cabinet, while the upper of the sections is constructed with the purpose in view of producing a 25 desk top for the convenience of the user of the cabinet.

Another object of this invention is the provision of a cabinet comprising a series 30 of hinged sections, each of which has located therein a plurality of pockets containing account books, said pockets being formed by connecting the opposite ends of the sections by a longitudinal partition, the upper edges 35 of the ends of the said sections having rigidly secured thereto strips, the forward edges of which are beveled to produce knife edges, whereby the leaves of the account books can be severed, the said strips also serving to yieldingly rest against the upper 40 sides of the account books and retain the leaves thereof against displacement when it is desired to fold them against the backs of the said account books.

A further object of this invention is the 45 provision of a cabinet comprising a series of sections containing a plurality of pockets, in which are located account books, the said sections each being provided upon its forward edge with a guide for the reception 50 of index cards, which may be readily adjusted and changed from one slide to the other to agree with the names on the account books located within the several sections.

55 A still further object of this invention is to improve and simplify devices of this

character, rendering them comparatively simple and inexpensive to manufacture, reliable and efficient in use, and readily operated.

With the above and other objects in view, 60 this invention resides in the novel features of construction, formations, combinations and arrangements of parts to be hereinafter more fully described and claimed, and illustrated in the accompanying drawings, in 65 which—

Figure 1 is a perspective view of my improved cabinet, and Fig. 2 is a transverse sectional view taken through a portion 70 thereof.

Referring to the drawing by characters of reference, the numeral 1 designates generally my improved cabinet, which consists of a series of sections 2, said sections being 75 hinged together at their rear edges, as at 3, and adapted to lie in superimposed relation to each other. The intermediate of these sections 2 consists of longitudinally extending bars 4, connected at their opposite ends by transverse bars 5, which are 80 connected at a point substantially intermediate the ends thereof by a longitudinally extending partition 6, which separates the frame into a pair of compartments or 85 pockets 7 and 8, the lower sides of which are closed by bottoms 9, which lie flush with the lower edges of the side and end bars 4 and 5.

Longitudinally extending retaining strips 90 10 are secured at their opposite terminals, as indicated by the numeral 11, to the opposite ends of the pockets, adjacent the outer sides thereof, in such manner that they will lie flush with the upper edges of the sections and 95 permit the closing thereof. These strips are formed to engage the leaves of the account books and permit the severing thereof, if desired. The strips 10 yieldingly engage the 100 ends of the account books and act as a spring clasp to hold the carbon leaves in folded position over the backs of the said books when it is desired to retain the leaves in the cabinet for reference.

The bottom 13 of the lowermost of the 105 sections 2 is formed slightly thicker than the before-mentioned bottoms 9 of the intermediate sections, and is extended upon the opposite sides and ends thereof, for the purpose of providing a base 14, upon which the 110 cabinet rests. This base 14 may be either placed upon a stand, table or the like, or

may have legs secured to its lower face, which support the cabinet within the convenient reach of a person using the same.

The upper of the sections 2 has hinged to its rear edge a top 5, which is constructed with the purpose in view of providing a desk top, upon which the account books contained within the pockets may be placed when in use.

10 A series of guides 16 are secured to the front edges of the sections 2, and contain a plurality of cards, upon which are located letters corresponding to the letters on the account books contained within the pockets of the several sections. Obviously these cards may be adjusted, if desired, and removed from the guides to correspond with the various names upon the account books.

20 A plurality of tabs 17 are secured to the bottoms 9 and extend beyond the ends of the account books, for the purpose of providing a means whereby the same may be readily removed from the pockets.

25 From the foregoing disclosures, taken in connection with the accompanying drawings, it will be manifest that a cabinet of the nature described is provided for which will fulfil all of the necessary requirements of such a device.

30 Having thus fully described this invention, what I claim as new and desire to secure by Letters Patent is:

A filing cabinet of the character described comprising a plurality of superimposed trays, hinges connecting the trays at their rear edges, each tray comprising a rectangular frame, a bottom within the frame, a longitudinally extending partition secured centrally of the end walls of the frame, said partition dividing the tray in two separate compartments, removing strips formed of flexible material secured to the bottom of each compartment, said strips being spaced from each other and extending along the bottoms and to the rear walls of the compartments and thence upwardly beyond the upper edges of said rear walls, account books within the compartments, said account books lying side by side and positioned so that their longitudinal axes lie in direct alignment with the longitudinal axes of the removing strips and retaining strips extending longitudinally of the compartments adjacent their forward walls and secured to the ends of the tray, said strips holding the account books against accidental displacement.

In testimony whereof I affix my signature in presence of two witnesses.

JOSHUA W. HARRIS.
